UNITED STATES PATENT OFFICE.

WILLIAM EDWARD BOEHCK, OF JERSEY CITY, NEW JERSEY, ASSIGNOR TO NEW YORK REVOLVING PORTABLE ELEVATOR COMPANY, OF JERSEY CITY, NEW JERSEY, A CORPORATION OF NEW JERSEY.

MANUALLY-OPERATED WINDLASS MECHANISM FOR PORTABLE ELEVATORS.

1,257,576.

Specification of Letters Patent. Patented Feb. 26, 1918.

Application filed April 19, 1913. Serial No. 762,236.

To all whom it may concern:

Be it known that I, WILLIAM EDWARD BOEHCK, a subject of the Emperor of Germany, residing at Jersey City, in the county 5 of Hudson and State of New Jersey, have invented certain new and useful Improvements in Manually - Operated Windlass Mechanism for Portable Elevators, of which the following is a specification, reference 10 being had to the accompanying drawings.

This invention relates to improvements in windlass mechanism and particularly to improvements in windlass mechanism for use in raising and lowering the load-carrying platform of a portable elevator; and an object of this invention is to provide windlass mechanism of the type just referred to with brake mechanism which may be accurately and readily controlled 20 and which will insure the rapid but safe descent of the load-carrying platform. Another object of this invention is to provide in a windlass mechanism of the type just referred to braking means which will automatically safeguard the workman from injury.

This invention consists in the combinations hereinafter claimed.

In the drawings illustrating the principle 30 of this invention and the best mode now known to me of applying that principle, Figure 1 is a side elevation of so much of a portable elevator as is necessary to illustrate this invention; Fig. 2 is a view looking 35 in the direction of the arrow A in Fig. 1; Fig. 3 is a detail in elevation of the brake mechanism; Fig. 4 is a section on the line B—B of Fig. 3; and Figs. 5 and 6 are details showing the operating crank.

In the upright frame members *a* are journaled the shafts *b*, *c* and *d*. The lowermost shaft *b* is the windlass-drum shaft and upon it are mounted fast the windlass-drum *e* and the spur-gear *f* fixedly connected therewith. The shaft *c* is the intermediate shaft and upon it is mounted a spur-gear *g* and a pinion *h* which is in mesh with the spur-gear *f* of the windlass-drum shaft. On the topmost shaft *d* there is mounted a pinion *i* which meshes with the spur-gear *g* on the intermediate shaft *c*. On the shaft *d* there is mounted loose or idly a brake-disk *j* having an annular flange *k* which is internally toothed and with the internal ratchet-

teeth *k'* of which there is arranged to engage the free toe-end of a spring-controlled pawl *m* carried by a pawl-carrier *n* mounted fast upon the shaft *d* and arranged to turn within the annular flange *k* of the brake-disk *j*. Around the windlass-drum *e* there is wound one end of a cable *o* the other end of which is attached to the load-carrying platform *p*. When the topmost shaft *d* is turned in the direction of the arrow C in Fig. 2, the windlass-drum *e* 55 will be turned through the train of gearing *i*, *g*, *h*, *f*, so as to wind up the cable and thereby to raise the load-carrying platform *p*. Furthermore, when the shaft *d* is turned in the direction of the arrow C shown in 60 Fig. 2, the toe-end of the pawl *m* will ride over the ratchet-teeth *k'*; but any retrograde or backward movement of the shaft *d* will cause the engagement of the toe of the pawl with the ratchet-teeth *k'* of the brake-disk 65 *j*. During the platform-raising movement of the windlass drum *e*, the turning of the brake-disk *j* will be resisted by brake-devices 70 which will now be described. The upright frame members *a* are connected by transverse horizontal frame-members *q* which support a horizontally-disposed bar *r* to each end of which is fastened an angle-bracket *s*. In the lower ends of these brackets *s* there is journaled a cam-shaft *t* (Fig. 85 3) mounted fast upon which is a pair of cams *u*. On each side of the brake-disk *j* there is arranged a brake-shoe or brake-jaw *v* the lower end of which is formed with an edged projection *w* and with an eye *x*. 90 Through these eyes *x* passes a bolt *y* the head *y'* of which rests against one of the edged projections *w* and the nut *y''* of which rests against the other of the edged projections *w* (Fig. 3). The upper bifurcated end of each of the brake-shoes *v* is provided with a pivoted block *z* having an eye *z'* through which passes the cam-shaft *t*; and between the blocks *z* of the upper ends of the brake-shoes there is mounted 95 upon the cam-shaft *t* a helical or coil spring 2 which tends to force the upper ends of the brake-jaws *v* apart. Each of the latter is formed with a laterally-extending lug 3 which carries a cam-roller 4. Normally the 100 sham-shaft *t* is so turned that the cams *u* press against the cam-rollers 4 and thereby force the brake-shoes *v* against the brake- 105

disk *j*, the coil-spring 2 being then compressed.

In order to turn the shaft *d* there is provided a crank 5 having a crank-handle 6 and formed with two sockets 7, 8, in one of which is adapted to engage the squared operating end *d'* of the operating-shaft *d*, while the other is adapted to receive the triangular operating end *t'* of the cam shaft 10. For convenience of operation, these sockets extend at right-angles to each other, as is clearly shown in Figs. 5 and 6.

Adjacent to the projecting triangular end *t'* of the cam-shaft *t*, there is fastened to the 15 machine frame a triangular guard-plate *t''* the inclined edge or side *t''* of which is so disposed that the workman may engage the walls of the socket 8 of the crank 5 with the projecting end *t'* of the cam-shaft *t* only 20 when the latter is so turned as to bring the cams *u* into engagement with the cam-rollers 4; that is, only when the brake-jaws *v* are forcibly pressed against the brake-disk *j*. This position of the crank 5 is shown 25 in dotted lines in Fig. 1. When the workman throws the crank 5 into the full line position of Fig. 1 to release the brake (Fig. 3), the crank 5 swings upwardly within the guard-plate *t''*, which then acts as a stop 30 or lock to prevent the removal of the crank 5 until the same is again thrown downwardly into the dotted line position of Fig. 1. Therefore, the workman cannot make 35 available the crank 5 for raising the load-carrying platform without first insuring that the windlass brake-mechanism is set or in braking position. In this way the workman is safeguarded from accidental injury and the goods upon the load-carrying 40 platform are also kept from harm due to an accidental dropping of the platform. It is preferred to have the projecting end *t'* of the cam-shaft *t* triangular in shape because it is difficult to turn with a wrench a shaft 45 so shaped and the workman is compelled to use the special crank 5 provided for the purpose.

From the foregoing description the operation of the mechanism will be readily 50 understood and may be briefly described as follows: In order to raise the load-carrying platform, the workman engages the squared end *d'* of the shaft *d* in the socket 7 and then turns the shaft *d* in the direction 55 of the arrow C shown in Fig. 2, as hereinbefore explained. During the upward movement of the load-carrying platform, the brake-shoes *v* press frictionally against the idle or loosely-mounted brake-disk and 60 prevent backward movement of the shaft *d*. In order now to release the brake so that the load-carrying platform *p* may descend under the influence of gravity, the workman is forced to remove the operating crank 5 65 from the end *d'* of the shaft *d*. In this way

it is insured that the workman shall not be injured by the backward throw of the operating-crank. To lower the load-carrying platform, the workman engages the end *t'* of the cam-shaft *t* in the socket 8 of the 70 crank and then throws the crank 5 into the full-line position shown in Fig. 1 and thereby turns the cam-shaft *t* so that the cams *u* are thrown out of engagement with the cam-rollers 4 (Fig. 3) whereupon the coil-spring 75 2 forces the brake-shoes *v* apart. The shaft *d* is now free to turn in the opposite direction and allow the load-carrying platform *p* to descend, the toe of the pawl *m* being now engaged with one of the ratchet-teeth *k'* of 80 the brake-disk *j*. In order to control the rate of descent of the load-carrying platform, it is necessary for the workman to keep his crank-handle in engagement with the cam-shaft. This is a distinct advantage, 85 since it keeps the workman at his post and on the alert and results in a more speedy movement of the load-carrying platform than would otherwise occur; for where a threaded shaft is used, it has been found 90 that the workman will generally adjust the shaft so that the load-carrying platform will be lowered at a slow rate and that, having adjusted the shaft in this way, he will leave the mechanism to itself. This slovenly style 95 of control results in a slow operation of the machine and loss of efficiency and is a decided drawback upon the use of a threaded shaft in the control of the brake-shoes.

In accordance with the provisions of the 100 patent statutes I have described the principle of operation of my invention, together with the apparatus which I now consider to represent the best embodiment thereof; but I desire to have it understood that the apparatus shown is only representative and 105 that the invention can be carried out by other means.

I claim:

1. A brake mechanism comprising a 110 brake-disk; brake devices arranged to engage said brake-disk; a shaft which applies said brake devices; removable means for turning said shaft and a guard-plate for preventing the disengagement of said means 115 and shaft while said brake devices are in released position.

2. The combination of a brake - disk; brake-shoes arranged to engage therewith; a shaft for controlling said brake shoes; a 120 device for turning said shaft, said device being normally detachable therefrom; and means for locking said device on said shaft in one position of said brake-shoes.

3. The combination with a manually- 125 operated operating shaft; of a brake-disk; brake-jaws therefor which control said brake-disk and therethrough said operating shaft; a manually-operated cam-shaft arranged to control said brake-jaws; and a 130

manually-operated detachable crank arranged to engage and turn said shafts alternately; said crank being formed with means for engaging the operating ends of 5 said shafts and being detachable therefrom; said operating ends having shapes that differ from each other; and the means for engaging said ends being shaped differently from each other.

Signed at Jersey City, in the county of 10 Hudson and State of New Jersey this seventeenth day of April, 1913, in the presence of the two undersigned witnesses.

WILLIAM EDWARD BOEHCK.
